PARISON TRANSFER MECHANISM

Charles Badger and Clyde C. Cook, Columbus,
Ohio, assignors to Owens-Illinois Glass Com-
pany, a corporation of Ohio

Application June 8, 1933, Serial No. 674,874

4 Claims. (Cl. 214—1)

Our invention relates to glass molding machines of the type in which parisons of glass are given an initial formation in blank or parison molds and then transferred to finishing molds in which they are blown to their finished form, such machines being used for making bottles, jars and other glassware. The invention relates particularly to apparatus for transferring the parisons from the blank molds to the finishing molds. Such apparatus is shown in connection with and as forming part of a two table machine comprising rotary mold tables arranged side by side and carrying, respectively, the blank molds and finishing molds. An object of the invention is to provide a transfer mechanism which is simple in construction, durable, reliable in operation and adapted for use with machines operating at high speeds.

Other objects of the invention will appear hereinafter.

20 In the accompanying drawings:

Fig. 1 is a side elevation of a machine embodying my invention.

Fig. 2 is a fragmentary plan view on a larger scale showing gearing for operating the transfer mechanism.

Fig. 3 is a section at the line III—III on Fig. 2.

Fig. 4 is a part sectional elevation of the transfer mechanism.

Fig. 5 is a sectional plan view of such mechanism, the section being taken at the line V—V on Fig. 4.

Fig. 6 is a section at the line VI—VI on Fig. 4.

Fig. 7 is a view showing a pair of tongs in open position.

Fig. 8 is a view of the same with the tongs closed about a parison.

Figs. 9 to 12 are views showing the transfer mechanism at successive periods during the transfer operation.

Fig. 13 is a view showing a valve and associated parts.

Fig. 14 is a sectional view of the valve.

Fig. 15 is a section at the line XV—XV on Fig. 14.

Figs. 16 to 18 illustrate a modification in which the transfer mechanism is driven by a pair of air motors.

Fig. 16 is a plan view showing the air motors and parts operated thereby.

Fig. 17 is a section at the line XVII—XVII on Fig. 16.

Fig. 18 is an elevation of mechanism shown in Fig. 16.

Referring particularly to Fig. 1, we have shown 55 a bottle forming machine of the press and blow

type. This machine comprises a blank mold table 20 and a finishing mold table 21 arranged side by side for rotation about vertical axes. An annular series of blank molds 22 are mounted on the blank mold table and a corresponding series of finishing molds 23 on the finishing mold table. Gears 24 and 25 are connected to the tables 20 and 21, respectively, and are driven by a motor 27 operating through gearing including a pinion 26 intermeshing with the gears 24 and 25. The driving mechanism may operate as is usual to index or rotate the mold tables step by step. Each step rotation of the tables brings a blank mold and a finishing mold into parison transfer position, permitting a parison to be transferred from the blank mold to the finishing mold.

The transfer mechanism, in general terms, comprises two parison gripping devices 30 each including a pair of gripping jaws for engaging a parison, vertical spindles 31 carrying the gripping devices, a yoke 32 in which the spindles are mounted for individual movement up and down, air motors 33 individual to said spindles for moving them vertically and for operating the gripping jaws, a rock shaft 34 to which the yoke 32 is attached, and means for oscillating the rock shaft and thereby carrying the gripping devices horizontally through an arc of 180 degrees. Each such movement of the gripping devices transfers a parison from a position over its blank mold to a position over the corresponding finishing mold and at the same time transposes the position of the gripping devices.

The transfer mechanism is supported by a horizontal channel iron or bar 35 mounted on vertical posts 36 and 37. The rock shaft 34 (see Fig. 4) is journaled in a hollow post or bearing sleeve 38, the upper end of which is flanged and secured by bolts 39 to the channel bar 35. The yoke 32 is connected by a key 40 to the lower end of the rock shaft. Each spindle 31 comprises a hollow shaft 41 and a rod 42 extending therethrough and having a limited vertical movement therein, as hereinafter set forth. Each of the gripping devices 30 comprises a pair of arms 43 formed with gripping or supporting jaws 44 designed to support a parison 45, said jaws when brought together surrounding the parison and engaging beneath the usual neck portion 46 formed on the parison. The arms 43 swing on a pivot pin 47 which extends through a spacing block 48 having a screw threaded connection (Fig. 4) with the lower end of the rod 42. A head 50 secured to the lower end of the sleeve 38 is formed with a slot or guideway 49 for the 55

block 48. The head 50 has a slot and pin connections 51 with the arms 43. It will be seen that with this construction, downward movement of the head 50 relative to the rod 42 and pivot pin 47 will cause outward swinging movement of the jaws and vice versa.

Each of the air motors 33 includes a cylinder 52, the upper end of which is formed with a flanged portion or head 53 which, as shown, is substantially circular, overlying the yoke 32 and thereby supporting the motor cylinder. The lower end of the cylinder is formed with a flanged portion or head 54. The tubular shaft 41 extends through holes in said heads 53 and 54. Coil springs 54^a are mounted on bolts 54^b, the latter extending freely through the yoke 32 and screw threaded into the head 53. The springs are under tension and hold the cylinder head 53 firmly seated on the yoke 32. Within the cylinder 52 is a piston 55. Above the piston and resting thereon is a plunger 56 which extends upward to and through the upper end of the cylinder. Keyed to the upper end of the plunger is a laterally extending arm 57. The upper end of the sleeve 41 has a screw threaded connection with the arm 57. Bearing blocks 57^a are bolted to the head 53 on opposite sides of the arm 57, said blocks being seated in a shallow channel 57^b in the upper face of the head 53. The plunger 56 is formed with flat surfaces 56^a against which the blocks 57^a bear as the plunger moves up and down. The rod 42 carries a disk 58 attached to the upper end thereof. Pins 59 secured to and extending upward from the head 53, provide stops which engage beneath the disk 58 and limit the downward movement of the rod 42 relative to the shaft 41 when the latter is in its lowered position.

The operation of the air motor 33 is as follows: Assuming the parts to be in the position shown at the left hand of Fig. 4, the gripping jaws are open as shown in Fig. 7. The weight of the shaft 41, plunger 56 and connected parts holds the head 50 in its lowered position relative to the rod 42 which is at this time supported on the stop pins 59, so that the gripping jaws are held open (Fig. 7). If, now, air is admitted to the cylinder 52 beneath the piston 55, the latter moves upward, thereby lifting the plunger 56, shaft 41 and yoke 50, so that the yoke operates to swing the gripping jaws together as shown in Fig. 8. The initial upward movement of the piston 55 thus operates to close the gripping jaws about a parison. The continued upward movement of the piston carries the gripping device upward, the rod 42 and shaft 41 now moving upward as a unit. When the supply of air is cut off from the motor the air in the motor cylinder is permitted to escape through an adjustable bleeder valve 60, allowing the spindle 31 to move downward until the disk 58 engages the stop pins 59. The shaft 41 and yoke 50 continue their downward movement, thereby opening the gripping jaws, the parts being brought to rest when they again reach the position shown in Fig. 4.

The mechanism for rocking the rock shaft 34 and thereby oscillating the gripping jaws, is as follows: A vertical drive shaft 61 (Figs. 1 and 2) is journaled at its lower end in a stationary arm 62 fixed to the upper end of a standard 63. The upper end of the shaft is journaled in a triangular bracket 64 attached to the angle bar 35. A pinion 65 fixed to the lower end of the shaft 61 runs in mesh with and is driven by the gear 24.

Keyed to the upper end of the shaft 61 is a crank arm 66. A connecting rod 67 connects the crank arm 66 with a gear pinion 68 mounted on a stud shaft 69 fixed to the bar 35. The gear 68 meshes with a gear pinion 70 keyed to the upper end of the rock shaft 34. The gears 24 and 65 are so proportioned that each step rotation of the mold tables rotates the gear 65 and drive shaft 61 through an angle of 180 degrees. The length of the crank 66 is less than the radial distance between the shaft 69 and the wrist pin 71 by which the rod 67 is connected to the gear 68, so that the rotation of the drive shaft 61 imparts an oscillating movement to the gear 68. This movement transmitted through the gear pinion 70 to the rock shaft 34 rotates the latter through an angle of 180 degrees each time the mold tables are indexed.

The air supply for operating the motors 33 is controlled by a valve 72 (Figs. 13 to 15) operated by or in synchronism with the movements of the mold carriages. Air under pressure is supplied through a pipe 86 connected to the valve casing 87 and communicates through a port 88 with a passageway 89 extending axially through the valve and communicating through ports 90 with pipes 91 and 92 which extend to the air motors 33. Rotation of the valve places the air pipe 86 alternately in communication with the air motors 33.

The operation of the transfer apparatus as a whole will be understood by reference to Figs. 9 to 11 which illustrate successive steps in a cycle of movements, and in which the two air motors 33 are designated I and II respectively. With the parts in the position shown in Fig. 9, both of the gripping devices 30 are open, one being directly over a blank mold 22 at the transfer position. A parison 45 has been projected upward in the usual manner. Air is now supplied to the motor I which operates, first, to close the jaws 30 about the parison and then to move the spindle 31 upward, thereby lifting the parison to the position shown in Fig. 10. The mold carriages are now given a step rotation. This movement of the mold carriages operates through the drive shaft 61 to rotate the shaft 34 through an angle of 180 degrees in the manner heretofore described, so that the motors I and II are transposed, this position of the parts being shown in Fig. 11. The air supply to the motor I is now cut off, allowing the spindle which carries the parison 45 to be lowered. The parison is thus projected downward into the finishing mold 23 directly therebeneath. The stop pins 59 arrest the rod 42 shortly before the motor piston has completed its downward movement so that the final downward movement of the shaft 41 operates in the manner heretofore described to separate the gripping jaws. This releases the parison so that it drops into position in the finishing mold. The parts are now in position for the next succeeding transfer operation. As the position of the two motors has been transposed, the motor II operates its gripping device for engaging the parison which is to be transferred during the next succeeding transfer operation.

Figs. 16 to 18 illustrate a modification in which the rock shaft 34 for oscillating the gripping devices is actuated by a pair of air motors 74 and 75. Pistons 76 reciprocate within the motor cylinders. Connecting rods 77 are pivotally connected at their inner ends to the pistons and at their outer ends are connected by wrists 78 to a

gear wheel 79 which drives a gear pinion 80 on a shaft 81. The shaft 81 corresponds to the drive shaft 61 (Figs. 1 and 2). It will be noted that the pistons 76 have driving connections through the rods 77 to the gear 79 on opposite sides of its axis so that when one piston is moved outward the other is drawn inward, thereby oscillating the gear 79. Said gear and the pinion 80 are so proportioned that each oscillation rotates said pinion through 180 degrees. Air for operating the motors 74 and 75 is supplied through pipes 83 and 84 under the control of a valve (not shown) which may be actuated in synchronism with the movements of the mold tables.

15 Modifications may be resorted to within the spirit and scope of our invention.

What we claim is:

1. Transfer mechanism comprising a vertically disposed rotatable shaft, a yoke carried by the shaft and rotatable therewith, vertical spindles mounted for up and down movement on said yoke, article engaging devices carried by said spindles, piston motors individual to said spindles, each said motor comprising a vertical cylinder and a piston, said motors being supported on and rotatable with said yoke and positioned laterally of their respective spindles, means operatively connecting the motor pistons to said spindles, means for actuating the motors and thereby individually lowering and lifting said spindles and causing each said article engaging device to engage and lift an article, and means for rotating said shaft and thereby transposing the positions of the spindles, article engaging devices and piston motors, rotatively of the axis of said shaft.

2. Parison transfer mechanism comprising a vertical shaft, means for rotating said shaft, a vertical spindle carried by said shaft, an article gripping device carried by said spindle, a piston motor carried by said shaft at one side of the spindle and comprising a vertical cylinder and piston, a plunger extending downward into the motor cylinder and resting on said piston, an arm connecting the upper ends of the plunger and spindle, said motor being operable to lift and lower the spindle, and means controlled by the

movement of the spindle for actuating the gripping means.

3. The combination of a vertical shaft, means for periodically rotating it about a vertical axis, a vertical spindle carried by the shaft at one side of said axis, said spindle including a hollow shaft and a rod extending therethrough, a pair of gripping jaws pivotally connected to said rod, means providing a connection between said hollow shaft and gripping jaws by which the jaws are opened and closed by a relative vertical movement of the said hollow shaft and rod, means comprising an air motor for periodically lifting and lowering the spindle in timed relation to the rotative movements of said first mentioned shaft, 10 said motor comprising a vertical cylinder carried by said first mentioned shaft at one side of the spindle and a piston in said cylinder, a plunger in said cylinder resting on the piston and projecting above the cylinder, an arm attached to the upper ends of the plunger and spindle, and means for causing said relative vertical movements of the hollow shaft and rod for operating said jaws. 15

4. The combination of a vertical shaft, means for periodically rotating it about a vertical axis, 20 a vertical spindle carried by the shaft at one side of said axis, said spindle including a hollow shaft and a rod extending therethrough, a pair of gripping jaws pivotally connected to said rod, means providing a connection between said hollow shaft and gripping jaws by which the jaws are opened and closed by a relative vertical movement of the 25 said hollow shaft and rod, means for periodically lifting and lowering the spindle in timed relation to the rotative movements of said first mentioned shaft, 30 and means for causing said relative vertical movements of the hollow shaft and rod for operating said jaws, 35 said means for lifting and lowering the spindle comprising a piston motor carried by said first mentioned shaft and including a vertical cylinder and a piston therein, a plunger movable up and down in the cylinder, and an arm connecting the upper ends of the 40 plunger and spindle.

CHARLES BADGER. 45
CLYDE C. COOK.
